Emil Edward Deister **INVENTOR**
BY
W. G. Burns **ATTORNEY**

UNITED STATES PATENT OFFICE.

EMIL EDWARD DEISTER, OF FORT WAYNE, INDIANA.

SCREEN.

Application filed July 15, 1926. Serial No. 122,545.

This invention relates to improvements in mechanical toys of that type in which material, such as dry sand, is passed through a series of operations. The object of the improvement is to afford a power driven mechanical toy for the handling and treatment of dry sand as a means of instructive amusement.

This object is accomplished by the construction illustrated in the accompanying drawings in which:

Fig. 1 is a side elevation of a construction embodying the invention; and

Fig. 2 is a plan projected from Fig. 1.

The characters of reference appearing in the description refer to parts shown in the drawings and designated thereon by corresponding characters.

The invention comprises a vehicle constituted of a platform 1 supported upon a pair of axles 2 and 3 each of which is provided at each of its ends with a wheel 4, upon which wheels the vehicle is movable. At one end of the platform is provided a pair of vertically disposed standards 5 that support near their upper ends a transversely disposed drive shaft 7, which shaft has on each end a sheave wheel 8, and also a second sheave wheel 9 adjacent one of the former sheave wheels. In the upper ends of said standards is mounted a transversely disposed counter shaft 10 having fixed thereon a sprocket wheel 11 and drive gear 12, which drive gear has actuated relation with the drive shaft 7 through intermediate gearing 13. A hand-operated crank shaft 14, provided with a gear 15 that meshes with said intermediate gearing 13, is arranged so that the counter shaft 10 may be actuated manually by turning the crank 16.

A bracket 17 positioned at the top of each of the standards 5 afford bearing support for said crank shaft and intermediate gear mechanism.

The end of the platform, opposite the standards 5, has projecting beams 18 in which is mounted a transverse shaft 19 having thereon a sprocket wheel 20, and upon the sprocket wheels 11 and 20 is mounted a conveying member consisting of an endless chain 21 having thereon a series of conveyer buckets 22 spaced apart, which conveyer member is actuated as the counter shaft 10 is rotated. An open chute 23 is supported at its lower end upon the beams 18, and at its upper end between the stand-

ards 5 and extends between the upper and lower lengths of the endless chain. The chute serves as a brace for the standards 5 and also receives droppings from the buckets of the conveyer member, which droppings are directed by the chute to the ground beneath the conveyer.

A hopper 24 is positioned on the standards 5 at a point beneath the countershaft 10 so as to receive materials discharged from the upper end of the conveyer member, and contiguous with the lower end of the hopper, and mounted upon the standards 5 is a bin 25 that extends outwardly from the standards and has in its lower end an outlet spout 26 which is controlled by a valve 27 arranged therein. In the top of the bin 25, and extending beneath the hopper 24, is arranged a vibratable screen 28 having fixed thereon an upwardly extending frame 29 in which is mounted a transverse shaft 30. Above each end of the shaft 30 is mounted a sheave pulley 31 to be actuated by a belt 32 that is trained on the corresponding sheave pulley 8 on the drive shaft 7. The shaft 30 has mounted thereon a fly wheel 33 having a counter weight 34 fixed eccentrically thereon so that the fly wheel rotates out of balance when the shaft 30 is actuated, and thus causing the screen to vibrate.

At the outer end of the bin 25 is positioned a horizontal rock-shaft 35 which has fixed thereon a catch box 36 for the reception of oversize materials that pass over the screen 28 from the hopper. The catch box tips when the rockshaft is actuated, so that its contents are thereby discharged. Upon one end of the rock-shaft is fixed an arm 37 which has connection with a hand operated windlass 38 by means of a cable 39, the windlass being mounted in the standard 35'. A spring controlled ratchet mechanism 40 has locking engagement with the windlass by which the windlass is prevented from retracting, and thereby the catch box is sustained in receiving position.

Upon the platform 1 is installed an electric motor 41 that has geared connection with the counter shaft 42, there being a sheave pulley 43 on the counter shaft that has a belt connection 44 with the sheave pulley 9 on the drive shaft 7. The motor is energized by current supplied by a battery 45, or other suitable source of electric energy, there being conductors 46 and a switch 47 arranged in proper connection between

the battery and the motor for the control of the motor circuit.

Upon the platform is mounted a brake lever 48 for actuating a brake 49 which is suspended from the platform and has frictional engagement with the adjacent pair of wheels 4, there being a latch 50 on the brake lever, having engaging relation with a sector 51 on the platform, for controlling 10 the brake.

In utilizing the invention, the vehicle is positioned upon the ground, with the lower end of the conveyer member extending into a pile of sand (not shown) and is held stationary by manipulating the brake lever so that the brake is applied. The electric current is then turned on by closing the switch, which causes operation of the motor, so that the conveyer member and the screen are actuated. The sand from the pile on the ground is carried by the conveyer buckets and deposited into the hopper from which it passes onto the screen. The slant and vibration of the screen cause the sand to move, the oversize particles passing over the screen into the catch box, while the undersize particles pass through the screen into a bin. As the catch box and bin become filled, they are emptied by opening the valve 27 in the discharge tube at the bottom of the bin, and by releasing the ratchet mechanism from engagement from the windlass, permitting the catch box to dump its contents.

35 What I claim is:—

1. In a portable sand sizing apparatus, a vehicle having vertical standards at one end thereof; a bin supported in an elevated posi-

tion by said standards and extending outwardly therefrom; a catch box hinged at the 40 outermost end of the bin, so disposed as to swing into discharging position under said bin; a latch controlled windlass having actuating relation with the catch-box and operable to sustain the catch-box in receiving 45 position; a screening mechanism positioned above the bin and discharging undersize material into the bin and oversize material into said catch-box; an elevator for supplying sand to said screen mechanism; and actuating means for the screening mechanism and elevator.

2. In apparatus of the class described, a bin supported in an elevated position and having a valve controlled outlet in its bottom; a catch-box hinged at the outer end of said bin and disposed so as to swing beneath the bin into emptying position; a latch controlled windlass operable to move said catch box into horizontal or receiving position; a screening mechanism arranged to discharge undersized material into said bin and oversize material into said catch box; and means for supplying said screening mechanism with material to be screened.

3. In combination with a portable screening mechanism, an elevated bin arranged to receive undersize material from said screening mechanism; a catch box having hinged support at the front edge of said bin and being adapted to swing beneath the bin when in position to discharge; and a latch controlled windlass operable to raise and hold said catch box in receiving position.

In testimony whereof I affix my signature.

EMIL EDWARD DEISTER.
